Primary Examiner — Michelle E. Wilson

(74) Attorney, Agent, or Firm — Prakash Nama; Global IP Services, PLLC

(57) CLAIM

The ornamental design for a silicon makeup brush cleaner, as shown and described.

DESCRIPTION

FIG. 1 is a front elevational view of a silicon makeup brush cleaner showing my new design;

FIG. 2 is a rear elevational view thereof;

FIG. 3 is a left side view in enlarge scale thereof;

FIG. 4 is a right side view in enlarge scale thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof; and,

FIG. 10 is a fourth perspective view thereof.

The broken lines shown in FIGS. form no part of the claimed design.
